PRINTING TAPE DISPENSER

Edwin W. Mason, Wyckoff, N. J.

Application August 29, 1944, Serial No. 551,720

2 Claims. (Cl. 101—227)

1

The invention relates to a dispensing device for tape, particularly the type which is transparent and adhesive coated on one side, such as is known as "Scotch tape." The invention relates more particularly to such a dispensing device which operates, at the same time that it dispenses a length of tape, to imprint any desired reading matter upon the adhesive coated side of the transparent tape.

Such adhesively coated transparent tape is conventionally used in place of string or cord to effect a closure of small packages, particularly by a retail establishment. Such transparent tape, if printed as it is dispensed, for instance, with the name and address, or any advertising matter, of the retail shop keeper, constitutes a valuable adjunct to retailing by simultaneously marking, labelling, sealing and identifying the packaged merchandise, to which the printed tape is applied.

An object of the present invention is to provide such a printing tape dispenser which is compact and suitable for use upon the counter of a retail establishment, is extremely simple in its operation and the replenishment of the source of supply of the tape, the changing, when desired, of the printed matter or message imprinted upon the tape, and which utilizes a medium for the imprint which will yield effective and clear printing without smudging. The apparatus of the present invention is also designed for the complete closure and housing of the tape and printing mechanism, offering distinct advantages not only of appearance but the prevention of any foreign matter, or dirt from getting into the mechanism and interfering with the clear and effective printing of the tape as it is issued from the dispenser.

I am aware that various prior methods and apparatus have been suggested for the printing of transparent or cellulose tape concurrently with the dispensing thereof from a container. However, none of these prior attempts has been successful commercially for the reason that they have been designed to operate with a printing medium completely unsuitable for the purpose of printing upon an adhesively coated cellulose tape as it is being dispensed.

One such prior attempt at a solution of the problem is evidenced by the patents to Bronfman 2,223,907 and 2,302,179, the former for the apparatus for printing on the adhesive side of an adhesive covered material, and the latter for a method of printing transparent adhesive tape. In the Bronfman patented structure and method,

2

there is utilized a printing medium broadly characterized as a quick drying ink but more specifically disclosed as a powdered pigmentary ink. Such powdered pigment is fed from a reservoir to a printing roller by means of a felt roller to which the powdered ink is directly applied.

I have found that such an apparatus and method, utilizing a reservoir of powdered pigment in the form of discrete particles is completely unsuitable and ineffective to yield a clear and smudge-free imprint upon the adhesive coated side of the cellulose tape.

In accordance with my invention and in accordance with the apparatus hereinafter described, I utilize a substantially solid body of printing medium in the form of a stick of chalk and a felt roller in contact with the stick of chalk abrading the solid body of printing material and transferring, by means of such felt roller, the abrading particles to a hard rubber roller with which the adhesive coated side of the cellulose tape is then brought into contact, effecting the imprinting of such adhesive coated side by the continuous rotation of the hard rubber roller.

By the use of this expedient, I am enabled to effect a very clear transfer of the imprint from the hard rubber roller to the adhesive coated side of the cellulose tape as the tape is dispensed from the apparatus and without any smudging of the imprint.

In the embodiment of my invention in the apparatus hereinafter described, I provide means for insuring the proper alignment of the tape to be printed and dispensed so as to provide for the ultimate collapsibility of the core supporting the tape.

My device is also designed with a view of securing a complete closure or housing of the tape and printing mechanism to prevent the entry of any dirt or other foreign material which by lodgment upon the section of the tape withdrawn from the source of supply would interfere with the proper printing of the adhesive coated side thereof by the printing mechanism.

In the accompanying drawings, I have illustrated a specific embodiment of my invention. In such drawings Fig. 1 is a vertical section through the printing tape dispenser constructed in accordance with my invention; Fig. 2 is a section on the line 2—2 of Fig. 1; Fig. 3 shows a strip of printed cellulose tape which has been dispensed from my apparatus after imprint thereof; Fig. 4 shows a fragment of a strip of similar nature illustrating a different width and type of imprint which may be effected by my apparatus by a simple change

or substitution therein; Fig. 5 is a section on the line 5—5 of Fig. 1; Fig. 6 is a section on the line 6—6 of Fig. 1; Fig. 7 is a section on the line 7—7 of Fig. 6; Fig. 8 is a perspective view of a metal compartment for receiving, by gravity, the abraded and unused particles removed from the chalk body by the felt roller and which should be collected in some reservoir, so as to protect the remaining portion of the apparatus therefrom; and Fig. 9 is a perspective view of a body of the printing material constituted of a stick of chalk which has been abraded on its melting surface with the felt roller.

Referring more particularly to the drawings, in which similar reference characters identify similar parts in the several views, 10 designates a base for the housing for my device, from one side of which extends upwardly an integral half 11 of the housing of the generally conical cross-section shown in Fig. 5, the housing being completed by the second half 12 extending upwardly from the opposite side of the base 10 and meeting the first half 11 along a central median line of the housing. From approximately the vertical center of the housing member 11 extends inwardly a boss 13 within which, by screw 14, is secured a shaft 15 providing a bearing for the tape holder 16. Such tape holder 16 is preferably constituted of a wooden block having rounded corners, upon which the tape core 17 may be mounted. The tape core 17 is mounted upon the tape holder by such tape core upon which it had been wound by the manufacturer, the tape core 17 and the roll of tape 18 being pushed back sufficiently upon the tape holder 16 to abut a metal disc member 19. Such metal disc member is secured to the tape holder 16 by a plurality of screws 20. It may also be preferably provided with a circular indentation 21 and two thumb recesses 22 to facilitate the application to, and removal from, the tape holder and metal disc, of the tape roll and core.

Opposite the boss 13 on the housing member 11 is a boss 23 extending from the housing member 12. Such boss, when the tape holder and roll of tape has been placed upon the shaft 15, retains such tape holder and roll of tape in position axially upon the shaft 15.

Substantially at the center of the lower edge of the housing member 12 and extending inwardly is a boss 24 from which extends a rounded pin 25 adapted to enter a recess 26 in the base 10.

From near the top edge of the housing member 12 extends still another boss 27 within which is mounted a spring-pressed pin 28 adapted to enter a corresponding recess 29 in the housing member 11, to complete the closure of the housing by first placing the pin 25 into its recess 26 in the base and then bringing the free housing member 11 into edge contact with the housing member 12 whereupon the two housing members will be locked together by the spring-pressed pin 28.

The base 10 may be provided with a rubber surface 30.

Extending inwardly from the thickened front portion of the housing member 11 is an idler roller 31 mounted upon a shaft screwed into such thickened housing portion, with a link 32 mounted upon the shaft, the link carrying at its free end, so as to extend inwardly of the housing, a shaft 33. Mounted upon such shaft is a wood roller 34 upon which is secured by suitable adhesive a hard rubber printing strip 35 carrying any desired legend or combination of print and design. Such roller and the hard rubber printing

strip may be readily changed by merely removing the roller 34 and substituting a different roller carrying a different hard rubber printing strip.

Below the printing roller 34, and in direct contact with the printing strip 35, is a felt roller 36 mounted upon a shaft 37 secured by a screw to the thickened portion of the housing member 11. The felt roller 36 is free to rotate upon the shaft 37. In contact with the lower surface of the roller is the upper face of a solid block of printing medium 38 such as a block of chalk.

The chalk supporting mechanism comprises a sheet metal cradle 39 secured to the housing member 11 by screw 40, the cradle having two upwardly diverging arms extending on each side of the felt roller 36. The block of chalk 38 is urged upwardly against the felt roller 36 by a spring 41 of the configuration shown in Figs. 1 and 7, the tension of the spring being secured by the spring coil 42 and the spring having a handle 43 extending outside of the cradle 39. Such handle 43 facilitates the release of the spring and thereby relieves tension on the block of crayon so that it may be removed and replaced at will.

Beneath the sheet metal cradle 39 is a powder collecting metal reservoir 44 shown in perspective in Fig. 8.

The two housing members 11 and 12, just forwardly of the printing roller 34, have an opening 45 of sufficient size to permit the easy withdrawal therethrough of the strip of tape 46 unwound from the roll 18. Upon the upwardly extending nose 47 of the housing is mounted a preferably serrated knife edge 48 by means of which, after a desired length of tape 46 has been withdrawn from the device, such tape may be cut.

In the operation of my novel printing tape dispenser, the leading edge of the tape 46 is grasped by the fingers of the operator and the tape pulled forwardly of the device. The tape is pulled forwardly to a sufficient extent to unwind from the tape roll 18 the desired length of tape which, as it is pulled forward, passes first under the idler roller 31 and then over the hard rubber printing strip upon the printing roller 34 by means of which the printing is applied to the sticky under side of the tape. When the desired length of tape has been withdrawn, the tape may be readily cut by the serrated knife edge 48.

In Fig. 3, I have illustrated a length of printed tape 49 which has been dispensed by my apparatus and upon which any desired printing has been effected in the course of withdrawing the tape from the dispenser. In such Fig. 3, I have shown a tape of the conventional width of $\frac{1}{2}$ inch, but, as shown in Fig. 4, a wider strip 50 of printed tape can also be printed and dispensed by my device for which provision is made by the excessive width of the printing roller 34 and of the felt roller 36.

As a matter of fact, a two color printed tape may be printed and dispensed by my device by employing two different colors of chalk or blocks of crayon on the same width of tape. This would only require the positioning of two different blocks of chalk, side by side, within the vertical portions of the sheet metal cradle 39, both of the blocks being pressed upwardly by the spring 41.

It will be noted that the housing for my printing tape dispenser is substantially completely closed except at the opening 45 through which the tape is withdrawn, so that the tape printing maximum is substantially closed to prevent the entrance of dirt and other foreign particles into

the mechanism and lodging upon either the printing mechanism or the tape, thereby causing smudging of the print or other interference with the effective operation of the device.

I claim:

1. In a printing dispenser for a pressure-sensitive adhesive coated tape, a housing constituted of a base, an integral vertical member, and a co-operating free vertical member adapted to be seated upon said base along its periphery and form, by edge-abutting relation with the integral member, a substantially complete closure, the combination of a tape roll holder rotatively supported from said integral vertical member, a printing roller, a hard rubber printing strip upon said roller, a felt pigment transfer roller positioned for free rotation below said printing roller, and a spring-pressed solid block of chalk in contact with said felt roller, a knife edge mounted upon the housing forwardly of the printed roller, a shaft extending inwardly from said integral vertical member, a link rotatively mounted upon such shaft, and a shaft extending from the free end of said link for supporting the printing roller.

2. In a printing dispenser for a pressure-sensitive adhesive coated tape, and having a base, a two-member housing thereon, one of said members being integral with said base, the combination of a tape roller rotatably supported from one of said housing members, an idler roller, a shaft 30

therefor extending from said integral housing member, a link rotatively mounted upon such shaft, a shaft extending from said link, a printing roller upon said shaft, a hard rubber printing surface upon said roller, a roller having a soft fabric surface positioned for free rotation below said printing roller, a sheet metal cradle beneath said roller, a block of chalk positioned within said cradle and in contact with the under surface of said transfer roller, and spring-controlled means for pressing said block of chalk against said transfer roller.
